UNITED STATES PATENT OFFICE

115,122

DESIGN FOR A SUIT

Adolph Oppenheimer, New York, N. Y.

Application March 18, 1939, Serial No. 83,663

Term of patent 3½ years

To all whom it may concern:

Be it known that I, Adolph Oppenheimer, a citizen of the United States and residing in Manhattan, in the city, county, and State of New York, have invented a new, original, and ornamental Design for a Suit, of which the following is a specification, reference being had to the accompanying drawing, forming part thereof, wherein

Fig. 1 is a front view of a suit showing my new design.

Fig. 2 is a rear view thereof.

The scarf is permanently attached.

The characteristic feature of my design resides in the combination on the specific suit disclosed of the specific breast pockets on the stitched and darted jacket in association with the tie collar and seamed skirt as shown.

I claim:

The ornamental design for a suit, substantially as shown and described.

ADOLPH OPPENHEIMER.
